BUCKLE FOR A SAFETY SEAT BELT

Edward L. Barcus, La Grange Park, Ill., assignor to
Pontonier, Inc., Chicago, Ill., a corporation of Illinois

Filed Dec. 2, 1965, Ser. No. 23

Term of patent 14 years

(Cl. D2—408)

FIG.1

FIG.4

FIG.2

FIG.5

FIG.3

FIG.6

FIG.7

FIGURE 1 is a perspective view of a buckle for a safety seat belt showing my new design;

FIGURE 2 is a top view of the buckle shown in FIGURE 1;

FIGURE 3 is a bottom view of the buckle shown in FIGURE 1;

FIGURE 4 is an end elevation of one end of the buckle shown in FIGURE 1;

FIGURE 5 is a side elevation of one side of the buckle shown in FIGURE 1;

FIGURE 6 is a side elevation of the other side of the buckle shown in FIGURE 1; and

FIGURE 7 is an end elevation of the other end of the buckle shown in FIGURE 1.

I claim:

The ornamental design for a buckle for a safety seat belt, substantially as shown.
